CLAIM

The ornamental design for a surgical portal driver, as shown and described.

DESCRIPTION

FIG. 1 is a front perspective view of a surgical portal driver showing our design;

FIG. 2 is a bottom perspective view thereof;

FIG. 3 is a top view thereof;

FIG. 4 is a first side view thereof;

FIG. 5 is a bottom view thereof;

FIG. 6 is a side view thereof, opposite that shown in FIG. 4;

FIG. 7 is another side view thereof, 90 degrees offset from that shown in FIG. 6;

FIG. 8 is another side view thereof, opposite that shown in FIG. 7; and,

FIG. 9 is an exemplary environmental view illustrating the surgical portal driver engaged with a working portal (also known as a guide cannula) according to the present invention.

In the drawings, the broken lines depict environmental subject matter only and form no part of the claimed design.
